UNITED STATES PATENT OFFICE.

ABRAHAM E. ALADALO, OF LEAD, SOUTH DAKOTA.

FIRST-AID BOX.

1,297,051.

Specification of Letters Patent. Patented Mar. 11, 1919.

Application filed August 23, 1918. Serial No. 251,146.

To all whom it may concern:

Be it known that I, ABRAHAM E. ALADALO, a citizen of the United States, residing at Lead, in the county of Lawrence and State of South Dakota, have invented certain new and useful Improvements in First-Aid Boxes; and I do hereby declare the following to be a full, clear, and exact description of the invention, such as will enable others skilled in the art to which it appertains to make and use the same.

The present invention relates to improvements in first aid boxes, and has for an object to provide a box for containing a first aid package which is adapted to be secured to a suitable support in shops, mills, or the like places, where accidents are likely to occur, and where the use of the first aid package may be necessary in such events.

It is an object of the present invention to provide a holder for a first aid package, in which the package will be held against tampering, but in full view and in readiness to be withdrawn from the holder when accident requires.

My invention will be more fully understood after reference to the accompanying drawings, in which like parts are indicated by similar reference symbols throughout the several views, and in which:

Figure 1 is a perspective view of a first aid box constructed in accordance with my present invention.

Fig. 2 is a vertical, central, sectional view through the box.

Fig. 3 is a similar view, showing the manner of applying the glass cover.

Fig. 4 is a horizontal, sectional view taken on the line 4—4 of Fig. 2.

Fig. 5 is a perspective view of the combined spring clip and reinforcing tongue; and

Fig. 6 is a perspective view of the improved slide.

Referring now more particularly to the drawings, wherein is shown but a single embodiment of which the invention is susceptible, 1 designates the rear wall of the first aid box which is in this instance made up of a single piece of sheet metal, bent in the manner hereinafter described.

At 2 and 3 are represented the top and bottom walls of the box, which are bent from the rear wall 1. The top 2 is provided with lateral extensions 4 and 5; while the bottom 3 is provided with similar lateral ex-

tensions 6 and 7; said extensions being bent over and overlapped in the manner best shown in Fig. 1, they being riveted or otherwise secured together, as indicated at 8 and 9, to form the end walls of the first aid box.

The extensions 6 and 7 are provided with the right angularly bent over parts 10, which form supports and guides for the glass cover as will hereinafter appear.

The rear rivets 8 and 9 are also employed to pass through flanges 11 and 12, which are bent from the vertical edges of the rear wall 1, and lie inside of the end walls to which they are attached by said rivets.

The top wall 2 is also provided with a forward extension which is bent down to form a flange 13, and beyond the flange 13 said extension is carried forwardly 75 and downwardly to provide a protecting hood 14.

In like manner the several lateral extensions 4, 5, 6 and 7 are all provided with bent over flanges 15 and 16 which lie in substantially the same plane with the upper flange 13 and form therewith ways in which the glass cover 17 may be slidingly fitted.

As shown to advantage in Fig. 3, the bottom or base 3 of the box is left unprovided with any such flanges, and the front end of this base 3 terminates short of the edges of the other walls, as indicated at 18, whereby to leave a space for the introduction of the glass cover 17 which is passed upwardly beneath the flanges 15 and 16 according to the manner shown in Fig. 3.

In Fig. 2 the glass cover is shown in its final position, where its upper longitudinal edge engages beneath the upper flange 13; 95 and I also prefer to provide a stop or rest 19 against which the opposite side of the glass cover may engage at the top thereof, in order to confine the same in the forward position and restrain the cover against being pushed inwardly of the box.

The cover 17 is adapted to be held and locked in place so that it is incapable of removal without being broken, and for this purpose I prefer to employ a slide 20 fitting within the base 3 of the box, and carrying a flange 21 which cooperates with the other flanges 13, 15 and 16 to hold the lower edge of the glass cover 17 in place in the box.

This slide 20 is also formed with a spring clip 22, preferably cut from the sheet metal

of which the slide is made, and bent upwardly with its forward edge terminating a distance from the flange 21 corresponding to the thickness of the glass cover 17, so as to 5 admit the lower edge of said cover in the manner shown in Fig. 2.

During the time that the slide 20 is being moved into place, the lower edge of the glass cover 17 will encounter and force the 10 spring clip 22 downwardly into the same plane with said slide, which will allow the slide to be moved into the final position shown in Figs. 1 and 2; but as soon as this final position is reached, and the spring clip 15 22 has escaped from the lower edge of the glass cover, the same will spring upwardly and snap beneath the cover, it being then impossible to withdraw the slide.

The spring clip 22 is reinforced in this 20 action by a spring tongue 23, the forward edge of which forms a guide for the glass cover. This spring tongue 23 is formed in one piece with a spring clip which is held in the box for receiving a first aid package, 25 which is indicated in dotted lines at 24.

This spring clip comprises a vertical rear strip 25, cut centrally from the same piece 30 of sheet metal, with two lateral spring arms 26 and 27, which are bent horizontally and provided at their free ends with gripping flanges 28 and 29. The package 24 is adapted to be received between the vertical rear strip 25 and the two flanges 28 and 29, and to rest on the horizontal arms 26 and 27.

35 The piece of sheet metal from which these parts are made is indicated at 30, and fits against the rear wall 1 of the box, the same being secured as by the rivet 31 which passes through the rear portion of the spring 40 tongue 23. The upper part of the vertical strip 25 is bent rearwardly, as indicated at 32, and the upper edge of this bent part 32 engages against the rear wall 1 of the box in the manner shown in Figs. 2 and 3, so 45 as to space the remaining portion of the strip below it away from said rear wall, in order that the strip may yield and move closer to the rear wall when the package 24 is inserted therein. This gives added spring 50 action.

At 33 and 34 I have shown fastening means which may pass through openings in the rear wall 1 of the box, and whereby the box may be attached to a wall or other suitable support in a shop, mill or the like place, 55 where accidents are apt to occur.

In use, the first aid box is put up in desirable numbers in appropriate places, such as 60 shops, mills, or the like, and whenever accidents occur the glass cover 17 is adapted to be broken by the butt of a tool, or other suitable instrument, so as to gain access to the package 24 within, which is removable from the spring clip by which it is carried 65 by an upward and forward motion. After

being broken, the glass cover 17, of course, will offer no resistance to the withdrawal of the slide 20, which is accordingly done in order to insert a fresh pane of glass after first placing a fresh package in the spring 70 clip.

The box prevents tampering with the first aid package 24 held therein, but at the same time holds the first aid package in full view so as to suggest itself when accidents occur, 75 and the arrangement is such as to enable ready and quick access to the package by breaking the glass.

The device also affords a cheap means for placing the device in the original condition 80 by simply inserting a new pane of glass.

The box keeps the first aid package from being handled, and the hood 14 and the remainder of the construction is such that the box is adapted to shed water, and may consequently be placed in the open or in wet or moist places, such as in mines. As the package is held away from the wall of the box, 85 it will not be apt to become wet or absorb moisture.

It will be obvious that various changes might be made in the herein described construction, and in the combination and arrangement of parts which could be used without departing from the spirit of my invention, and I do not wish to be limited to 95 such details except as pointed out in the claims.

I claim:

1. A device of the character described, 100 comprising a box, a frangible cover for the box, fixed means held on the box for confining the cover in place, and removable means co-operating with said fixed means to hold the cover against removal except by 105 breaking, said removable means having a locking tongue adapted to snap behind the cover to prevent the withdrawal of said removable means, substantially as described.

2. A device of the character described, 110 comprising a box, a frangible cover for the box, fixed parts along the edges of the box opening to confine the cover in place, one edge of the box opening being left free of such parts to admit the cover, a slide fitting 115 within the box and bearing against one edge of the cover at the place where the cover is admitted, and a spring tongue on said flange adapted to snap behind said cover when the slide is pushed home, substantially as de- 120 scribed.

3. In a device of the character described, 125 a box, means whereby the box may be held on a support, said box adapted to hold a first aid package, a glass cover for the front of the box, lateral guideways for slidably receiving the side edges of said glass cover, means for confining the upper edge of the glass cover, the lower front portion of the box being adapted to admit the 130

cover to said guideways, a slide passing within the box at the lower front part thereof and adapted to engage beneath the lower edge of the glass cover to hold same 5 in place, and means for locking said slide in place and adapted to prevent its removal without breaking the glass cover, substantially as described.

4. A device of the character described 10 comprising a box adapted to contain a first aid package and having means whereby same may be held on a suitable support, guideways at opposite sides of said box, a flange along the top edge of the box, a hood 15 projecting from said flange, a glass cover slidably received in said guideways and beneath said flange, a slide adapted to fit within said box and to engage beneath the lower edge of said glass cover, and a spring tongue 20 carried by said slide and adapted to snap behind said glass cover when the slide is pushed home, substantially as described.

5. A device of the character described including a metallic box, means carried by 25 the rear wall of the box for attaching same to a support, flanges bent over from the side walls and from the top wall of the box, means carried within the box for forming 30 guideways with said flanges, a glass cover adapted to slide in said guideways, a slide adapted to fit against the edge of said glass cover when in place, a flange on said slide extending in front of the lower edge of said 35 glass cover, and means carried by the slide for holding the latter in place until the glass is broken, substantially as described.

6. A device of the character described in-

cluding a box made of a single piece of sheet metal composed of a rear wall, top and bottom walls having lateral extensions, said 40 lateral extensions being bent over to provide side walls for the box, flanges bent from the top and side walls of the box, a lower wall bent from the rear wall and left free of flanges, a glass cover adapted to 45 slide past the free end of said lower wall and within said flanges, means within the box to hold a first aid package, a slide passing within said lower wall and having a flange to engage the lower edge of said 50 glass cover, and a spring latch carried by said slide and adapted to snap up behind said cover, substantially as described.

7. A device of the character described, including a box adapted to be attached to a suitable support, a spring clip in said box, a first aid package placed in said spring clip, said box having one side thereof open, flanges bent from the walls of said box 60 about the open end thereof on three sides of the box, the remaining side of the box being left free, a glass cover adapted to be slid in through the free side of the box and beneath said flanges, a spring clip adapted to snap beneath the end of said glass cover at the free side of the box whereby to lock the same in place, a spring reinforcing tongue forming a part of said first named spring clip and adapted to supplement said last named spring clip, and a hood forming 65 an extension of the flange on the upper side of the box, substantially as described. 70
